[57] CLAIM

The ornamental design for a snap-on shroud for caster, as shown and described.

DESCRIPTION

FIG. 1 is a perspective view of a snap-on shroud for caster, showing my new design.

FIG. 2 is a right-hand side elevational view thereof.

FIG. 3 is a top plan view thereof.

FIG. 4 is a bottom plan view thereof.

FIG. 5 is a rear elevational view thereof.

FIG. 6 is a front elevational view thereof.

FIG. 7 is a section therethrough taken at line 7—7 in FIG. 6 and viewed in the direction of the arrows.

The appearance of the left-hand side is a mirror image of that of the right-hand side shown in FIG. 2.

The appearance of a section viewed in the direction opposite arrows 7—7 in FIG. 6 would be a mirror image of that shown in FIG. 7.
